ADJUSTABLE COMBUSTION CONTROLLING APPARATUS

Filed Feb. 3, 1928

Inventor

Louis Hoedt

By his Attorney, Fred K. Richards

UNITED STATES PATENT OFFICE.

LOUIS HOEDT, OF BROOKLYN, NEW YORK.

ADJUSTABLE COMBUSTION-CONTROLLING APPARATUS.

Application filed February 3, 1928. Serial No. 251,514.

The invention relates to combustion controlling apparatus for furnaces, more particularly of the household type such as the ordinary steam boiler furnace in common use—although with certain modifications of the heating system the novel control may be applied equally well to hot water heating apparatus; and comprises a supplementary regulating attachment therefor.

10 The invention is adapted especially to heating apparatus in which there is employed a forced draft for the fire; and it has for its object to accelerate the cut-off action of the usual regulator employed, as the pressure controlled diaphragm apparatus of a boiler, for example, thus equipped for forced draft combustion, and to check for a predetermined and adjustable period throwing into operation again the draft producing apparatus, so that overheating by said furnace will be avoided and economy in fuel consumption effected.

15 A further object of the invention resides in certain details of construction of the novel regulator apparatus whereby it is not entirely dependent on the existing boiler pressure or the like, but its return to position for throwing into action the forced draft mechanism may be damped or caused to lag more or less behind the movement of the usual regulator in order that a better and more economical temperature regulation is attainable, the changes not being very marked from the particular point to which the governing apparatus has been set. The invention contemplates, also, adjustable means which may readily be set for maintaining predetermined temperature conditions.

20 By thus affording a very close regulation of the furnace operation, it is possible to install a forced draft mechanism with household types of boilers and permit thereby of the utilization of cheaper grades of coal, such as No. 2 buckwheat or rice sizes and mixtures thereof.

25 In the accompanying drawings which illustrate the invention.

Fig. 1 shows in side elevation the novel regulator attachment associated, for example, with a steam boiler and blower apparatus for the furnace thereof, said attachment being indicated as controlling the operation of the forced draft mechanism.

30 Fig. 2 is a detail fragmentary longitudinal

section of the novel governing member employed, and Fig. 3 is a plan thereof.

Fig. 4 is a fragmentary sectional view illustrating the conditions prevailing in the governing member in one of its extreme positions.

Fig. 5 is a detail fragmentary elevation of the adjustable connection between the power switch and the regulating mechanism.

Referring to the drawings, 10 designates a steam boiler of the ordinary household type but in connection with which there has been installed a blower 11 for introducing air under pressure into the sealed ash pit 12 of the furnace. The said blower is to be driven by an electric motor 13 to which power is supplied by leads 14 from switch mechanism of any well-known standard or special type inclosed in a suitable switch box 15, and to which mechanism are connected the power mains 16.

35 This switch mechanism, furthermore, is designed to be controlled from the novel regulator device hereinafter set forth as through an extension or arcuate arm 17 attached thereto and having a longitudinal slot 18 therein into which fits one end of a connecting link 19. Moreover, the said end of the latter, through a roller 19', slides in the arcuate slot 18 of the arm; and over the said arm, in turn, is arranged to be moved 40 for adjustment a stop member 20 having a spring-pressed detent 21 to hold said stop at various points along the arm through engagement with the toothed upper edge thereof. Corresponding graduations 22 are provided beneath the same along the face of the arm, so that the extent of travel of the end of link 19 may be set to obtain different temperature conditions conforming to the graduations.

45 The opposite end of the said link is pivotally connected to the longer arm of the oscillatable controlling bar 25 of the usual pressure controlled diaphragm regulator 26 associated with steam boilers and the like.

50 Rigidly supported at the requisite angle on said bar 25, as by a pair of straps 27 or the like extending therefrom on the switch side of said diaphragm regulator, is a control member containing a suitable liquid—55 preferably a light oil or glycerine. This control member comprises two boxes or compartments 28 and 29 of substantially

equal and comparatively large capacity and connected by a tube 30 of reduced cross-sectional area, the connecting tube preferably being square in cross-section, and the compartments constructed as square boxes. The box 29, moreover, is at a lower level than the box 28, the top of the former being substantially on line with the bottom of the latter; and an air connection 31 is provided between the two said boxes and having also vent openings 32 along its underside so that flow between said two boxes may be free except as regulated in manner hereinafter described. A partition wall 33 extends 10 across the upper end of the tube 30 to a short distance below the top of the same, leaving, however, an appreciable opening 34 thereat so that fluid in passing from the box 29 to the box 28 may be rapidly discharged 15 into the latter through said opening. In the reverse direction, however, the return flow is impeded or restricted to that passing through a small opening 34' controlled by means of an adjustable needle valve 35, the 20 return of fluid from box 28 to box 29 being all through said valve-controlled opening, and a splash plate or baffle member 36 being provided to this end within box 28 across the same at the opening 34' so as to check 25 return through this opening and prevent any possible splashing of liquid into the vent connection 31.

As hereinbefore stated, the novel regulator or control member is rigidly connected to the controlling bar 25 which, through the operating bell-crank 37 of the pressure controlled diaphragm regulator, is oscillatable about the fulcrum 38 and will thus impart similar movement to the control member. Thus, due to the rise and fall of the bell-crank 37 of the diaphragm regulator under the different thermic conditions, the control member will be caused to assume various angular positions with the rate of flow of liquid between compartments of said member different in opposite directions.

For example, when the furnace has cooled down, the cycle of movements will be as follows, the position of the control member then being the lower of the two positions shown in dotted lines; and in which position all of the liquid is contained substantially in the box 29 with the arm 17 in its lowermost position in which the switch 15 closes the circuit to the motor. This brings about an increase of temperature, bell-crank 37 then gradually rising and lifting with it the control member to the horizontal position indicated in full lines and to a point beyond the same where the level of the box 28 is somewhat below that of the box 29, whereupon, as the member becomes overbalanced, a rapid delivery of the liquid from the latter into the former through the opening 34 will take place and cause a sudden lifting of the

controlling bar 25 to the upper of the two positions indicated in dotted lines. This also swings with it the arm 17 to break the circuit at the switch 15 and shut off the blower.

The time required for this operation depends upon the amount of liquid in the container 29 as well as area of the opening 34 and is initially determined to suit the desired conditions. The amount of liquid and capacity of the compartments, however, should not be such that the liquid will rise appreciably above the level indicated in Fig. 4; that is to say, be somewhat below the baffle 36 when compartment 28 is in its extreme lowered position shown. A snap switch action is also thereby attained as the final overbalancing takes place suddenly.

Thereupon, the bell-crank begins to drop gradually, bar 25 following the bell-crank 37 actuating member 39 until the lower end of the link 19 sliding through the slot 18 contacts through its roller 19' with the stop 20. This will introduce sufficient resistance to prevent further downward movement of said control member and the bar 25 to which it is attached; but as the control member is then substantially in the horizontal position indicated in full lines, the liquid from box 28 will return to the box 29 but only slowly and as determined by the opening 34', which thus affords a means for regulating the time for again introducing the forced draft to the furnace through operation of the blower 11. When substantially all of the liquid has returned to the box 29, there will be sufficient weight exerted on bar 25 to force downwardly the arm 17 to the lowermost position, shown in dotted lines, in which the switch is again closed and the cycle of operation is repeated.

It will be noted that the short leverage on the box 28 side and the fact that the liquid in this compartment overbalances the apparatus, makes it impossible to actuate the switch member 15 to close the motor circuit until such time as appreciable liquid in the said compartment has percolated through the needle valve controlled opening to the compartment 29, when the snap action again occurs to close the switch. A considerable range, say from one minute to one hour, is thereby afforded in the restoration of the blowing operation which, it will be appreciated, makes for economical operation of the furnace.

A further regulation as well as adjustment in the installation of the controlling apparatus is afforded by the setting of the stop member 20 along a small length of the inner end of the arm 17, it being appreciated that the longer the leverage afforded at this arm the less effort will be required to trip the switch and consequently less time required for sufficient liquid to flow from

the compartment 28 to the compartment 29 for this purpose.

The present application is a continuation in part of the previous application filed by me April 21, 1927, Serial Number 185,393.

I claim:

1. In a heating system embodying a furnace, an electrically operated blower device for controlling the combustion of fuel therein, a movable regulator member controlled by the thermal conditions prevailing in the furnace, and switch mechanism for controlling the supply of power to the said blower; the combination with an oscillatable bar of said regulator member; of a liquid-containing member carried by said bar; a link pivotally connected with the bar; an arm extending from the switch mechanism and slotted longitudinally and the lower end of said link being movably connected into the slot thereof; and an adjustable stop member movable on said arm to determine the extent of movement of the link end.
2. In a heating system embodying a fur-

nace, an electrically operated blower device 25 for controlling the combustion of fuel therein, and temperature regulator member of said furnace; the combination with an oscillatable bar of said regulator; of a control member rigidly carried thereby and embodying a liquid-containing member divided into 30 two compartments having communication with each other through an upper and a lower opening in one of the compartments; and means for controlling the flow through 35 the lower opening to delay return movement of said regulator bar over its actuating range; a switch member operated by the movement of said bar to control the circuit to the blower device; a link pivotally connected with the bar; and an arm extending from the switch mechanism and slotted longitudinally and the lower end of said link being movably connected into the slot there- 40 of.

In testimony whereof I affix my signature.

LOUIS HOEDT.
